UNITED STATES PATENT OFFICE.

HIPPOLYTE A. MARINONI AND FRANÇOIS NOEL CHANDRÉ, OF PARIS,
FRANCE, ASSIGNORS TO RICHARD MARCH HOE.

IMPROVEMENT IN PRINTERS' QUOINS.

Specification forming part of Letters Patent No. 40,081, dated September 22, 1863.

To all whom it may concern:

Be it known that we, HIPPOLYTE A. MARINONI and FRANÇOIS NOEL CHANDRÉ, both of Paris, in the Empire of France, have invented a new and useful Improvement in Quoins and Furniture for Locking up Forms of Type for Printing; and we do hereby declare that the following is a full, clear, and exact description of the same, reference being had to the accompanying drawings, forming a part of this specification, in which—

Figure 1 is a plan of a chase containing a form of type locked up by our invention. Fig. 2 is a longitudinal section of the same perpendicular to the face of the form. Fig. 3 is a side view of one of the quoins on a larger scale than Figs. 1 and 2. Fig. 4 is a transverse section of a piece of the furniture on a scale corresponding with Fig. 3. Fig. 5 is a plan of a piece of furniture suitable for small job-work. Fig. 6 is a view of a key for locking up and unlocking the form.

Similar letters of reference indicate corresponding parts in the several figures.

This invention consists in the construction of the quoins in the form of rollers with surrounding recessed teeth or cogs, and the furniture with racks or series of teeth or cogs to gear with the said teeth or cogs on the quoins, such quoins being applied to roll between the furniture and the chase, or between two sticks of furniture and being turned by a key to move them from a wider to a narrower portion of the taper space between the furniture and the chase or between two pieces of furniture, and thereby made to tighten up the type in the page or pages and tighten up the page or pages in the chase.

To enable others skilled in the art to make and use our invention, we will proceed to describe it with reference to the drawings.

A A are the quoins, which may be of brass or other metal, and may be cast of the required form. a a are their recessed teeth or cogs, so arranged as to leave flange-like bearing-surfaces b b above and below them, the said surfaces forming portions of the periphery of a cylinder. The ends of the teeth a a are just within the said surfaces b b, by which they are protected from contact with the chase G or with any portion of the furniture but the tacks or cogs provided thereon. The depth

of these quoins corresponds with the depth of the chase and furniture. c c are holes, of square or other suitable form, provided in the centers of the quoins for the reception of the key D, Fig. 6.

E F represent furniture, consisting of a side-stick and a foot-stick, straight on the inner side which comes next the form d d, and having the outer side, which comes next the quoins, formed with a series of inclinations, e e, which may all have one direction, as illustrated in E, or opposite directions, as illustrated by F.

f f are the racks or series of teeth or cogs provided on the outer sides of the furniture to gear with the teeth or cogs a a of the quoins, so constructed and arranged as to allow the cylindrical bearing-surfaces b b of the quoins to bear upon the smooth surfaces e e above and below them. The straight sides of the furniture which come next the type in the form are roughened or toothed, as shown at g in Fig. 5, to give it a firm hold upon the exterior of the form. The piece of furniture shown in Fig. 5, it will be seen, has but one inclination, e, which may be sufficient for very small forms. The furniture may be made of malleable cast-iron, and the racks cast upon it.

To lock up the form the chase is put on and the furniture put into it in the usual manner, and the quoins are then placed in the widest parts of the taper spaces h h, between the chase and furniture, and turned by the key D in the direction of the arrows shown upon them in Fig. 1, when their teeth or cogs a a roll upon the racks f f of the furniture, and their surfaces b b roll upon the smooth inclined surfaces e e, and they are thereby forced into the narrowing portions of the spaces h h, and so caused to act in a similar manner to wedges, and press the furniture against the form, and so lock the type together and lock it in the chase. To unlock the type it is only necessary to turn the quoins in the opposite direction.

In forms of more than one page in which the pages are separated by the furniture and interposed quoins only, only one of the two pieces of furniture employed between two pages requires to be furnished with a rack and the other may be a simple straight piece.

The advantages of this invention consists in

the greater facility afforded for locking up forms, and in the greater durability of the quoins.

What we claim as our invention, and desire to secure by Letters Patent, is—

The combination of toothed or cogged roller quoins and furniture having corresponding

racks, teeth, or cogs, substantially as herein described.

HIPPOLYTE AUGUSTE MARINONI,
FRANÇOIS NOËL CHANDRÉ.
